INVENTOR:
BY John A. Minshull
Oscar L. Owen
ATTORNEY.

UNITED STATES PATENT OFFICE.

JOHN A. MINSHULL, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS.

SPINNING, TWISTING, AND LIKE MACHINE.

Application filed January 15, 1925. Serial No. 2,562.

To all whom it may concern:

Be it known that I, JOHN A. MINSHULL, a citizen of the United States, residing at Whitinsville, in the county of Worcester, 5 Commonwealth of Massachusetts, have invented certain new and useful Improvements in Spinning, Twisting, and like Machines, of which the following is a specification, reference being had therein to the 10 accompanying drawings.

The invention relates to improvements in foot boards of spinning, twisting and like machines, and the object of the invention is to provide apparatus which will be simple 15 and durable in construction and efficient in operation.

A further object is to provide an apparatus by means of which the duties of the operative are more efficiently performed.

20 Another object is to provide improved means whereby damages to the spindles and ring rails are prevented.

In the operation of spinning and twisting machines the operative has frequent occasions to change the supply of spools in the creel located on the upper part of the machine. In machines as at present constructed this is a tiresome operation especially to operatives of medium height, and

25 30 in order to make it easier for the operative a stationary step is arranged on the floor alongside of the machine, which answers the purpose but has the disadvantage of blocking the working space between two adjacent machines.

35 In my improvements as shown and described herein, I eliminate this objectionable feature by providing a foot board of suitable height from the floor that, when not in use swings up out of the way 40 and when in this position its construction serves as a guard preventing damage to any of the projecting parts of the spindles and ring rails that might otherwise be bumped and broken by trucks passing 45 through the space between adjacent machines.

Referring to the drawings, which illustrate merely by way of example a suitable embodiment of my invention; Figure 1 is a 50 perspective view of a well known type of twisting machine showing my improvement in operative position thereon. Figure 2 is an enlarged sectional end elevation on line 2-2 of Figure 1, showing my im-

proved construction in operative position in 55 full lines and in dotted lines its inoperative position. Figure 3 is a front elevation of one of the foot board supporting arms and its hanger. Similar numerals refer to like parts throughout the several views.

60 In the drawings, 10 and 11 are the head and foot ends respectively of a common type of ring twisting machine, 12 is a stationary rail connecting the two ends together. A 65 plurality of L shaped hangers 13 are bolted to this rail. On the lower end of each hanger are stationed ears 14 and 15 holding a stud or pivot 16 on which an arm 17 is swingable. The foot board is held in its 70 horizontal operative position (see full lines in Figure 2) by the side of the notch 19 on the arm 17 abutting against the lower end of the hanger 13. The stud 16 is provided with an enlarged end 20 serving as 75 a support for a coiled spring 21, one end 22 of which is fastened to the hanger 13 and the other end 23 abuts against the underside of the foot board, the tension of all 80 the springs together being sufficient to swing the foot board out of its operative 85 position, whenever the operative steps from the board, into its inoperative position as shown in dotted lines in Figure 2.

By this construction when the operative 90 desires to attend to the creel 24 he swings the foot board down to a position where he may easily step up onto it and thus be in a position where he may easily reach the creel without undue exertion. After 95 finishing his attentions to the creel he steps to the floor and the foot board automatically swings into its inoperative position close to the side of the machine out of the way of any operations along the side of the machine.

Underneath the outer side of the foot board 18 a rail 25 is fixed which serves to strengthen the board and also acts as a guard to prevent trucks, passing along the side of the machine, from hitting the ring rail 26 and the foot board supporting arms 17.

What I claim is:

1. In a machine of the character specified having a rail connecting the end frames of the machine, a plurality of hangers in a stationary relation with said rail, a swingable arm pivoted to each hanger, a board

supported by the arms, an abutment on each arm cooperating with the end of its supporting hanger, and means to automatically swing the board from its operative position 5 to its inoperative position against the side of the machine.

2. In a machine of the character specified having a rail connecting the end frames of the machine, a plurality of hangers in a stationary relation with said rail, two ears projecting from the lower end of each hanger, a stud supported by each pair of said ears, an arm swingable on each stud, a board supported by the arms, an abutment on each 10 arm cooperating with the end of its supporting hanger, and a coiled spring mounted on each stud having one end fixed to the hanger and the other end abutting against the underside of the arm whereby the resiliency of the springs operate to swing the board from its operative position to its inoperative position against the side of the machine.

3. In a machine of the character specified 25 having a rail connecting the end frames of the machine, a plurality of hangers fixed to said rail, a swingable arm pivoted to each hanger, a board supported by the arms, manually operated means to swing the board 30 into a horizontally operative position and

means to automatically swing the board from its operative position to an inoperative position against the side of the machine.

4. In a machine of the character specified 35 having a rail connecting the end frames of the machine, a plurality of hangers fixed to said rail, a swingable arm pivoted to each hanger, a board supported by the arms adapted to assume a horizontal operative position under the influence of the weight 40 of the operative, and means to automatically swing the board from its operative position to an inoperative position on the removal of the weight of the operative.

5. In a machine of the character specified 45 having a rail connecting the end frames of the machine, a plurality of hangers in a stationary relation with said rail, a swingable arm pivoted to each hanger, a board supported by the arms adapted to assume 50 a horizontal operative position under the influence of the weight of the operative, a guard member attached to the underside of the board and means to automatically swing the board from its operative position to an 55 inoperative position against the side of the machine.

In testimony whereof, I have signed this specification.

JOHN A. MINSHULL.
